(57) CLAIM

The ornamental design for a double plug toe thong footwear, as shown and described.

DESCRIPTION

FIG. 1 is a perspective view of a double plug toe thong
footwear, shown in use;

FIG. 2 is a top view thereof;

FIG. 3 is a bottom view thereof;

FIG. 4 is a first side view thereof;

FIG. 5 is a second side view thereof;

FIG. 6 is a front view thereof;

FIG. 7 is a rear view thereof; and,

FIG. 8 is an enlarged perspective view of a double plug toe thong footwear.

The broken lines of the figure drawings illustrate environment and form no part of the claimed design.
